UNITED STATES PATENT OFFICE

ELLIS HARTLEY, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS

APPARATUS FOR SPINNING YARN

Application filed March 4, 1930. Serial No. 433,113.

This invention relates to apparatus for spinning yarn and more particularly to the yarn spinning apparatus shown and described in my prior Patent No. 1,639,406, issued August 16, 1927.

It is the object of my invention to improve the apparatus therein shown by the provision of an annular flange or guiding member below the spinning ring, by which provision the yarn is more effectively guided to the bobbin and the use of an open type traveler is facilitated.

My invention further relates to arrangements and combinations of parts which will be hereinafter described and more particularly pointed out in the appended claims.

A preferred form of the invention is shown in the drawings, in which

Fig. 1 is a sectional side elevation of parts of a spinning frame embodying my improvements; and

Fig. 2 is a sectional side elevation of the cap and associated parts on an enlarged scale.

Referring to the drawings, I have shown parts of a spinning frame in which a plurality of spindles 10 are mounted in a fixed spindle rail 12. The spindles 10 are normally held in fixed position but are adjustable vertically, being provided for this purpose with a helical groove 13 in which the rounded point of a set screw 14 is seated. By turning the spindle angularly, the vertical adjustment thereof in either direction is accomplished.

Bobbins B are supported on spindle whirls 16, mounted on supports 17 carried by the bobbin rail 18. The whirls 16 are freely rotatable about the axes of the spindles 10 and are movable vertically with the bobbin rail 18.

Caps 20 are mounted on the upper ends of the spindles 10 and are each provided with a depending conical portion encircling and largely enclosing the bobbins B. The construction thus far described is usual in a cap spinning frame.

A collar 22 is threaded on the lower end of the cap 20 and provides a support for a spinning ring 24 which is clamped on the collar

22 by a locking ring or nut 26. This construction is along lines similar to that disclosed in my prior patent above identified.

An open type traveler T is mounted on the spinning ring 24 and guides the yarn Y as it is drawn downward from feed rolls 30 through a yarn guide or eye 32. The traveler T is preferably of the type shown and described in my prior Patent No. 1,746,154, issued February 4, 1930.

My present invention relates particularly to the provision of an annular guiding member or flange 40 mounted below the ring 24. Preferably the guiding member 40 is clamped between the conical lower portion 42 of the collar 22 and the conical inner face 44 of the ring 24. The lower part of the guiding member 40 is in the form of an outwardly and downwardly inclined flange which projects below the path of the traveler T.

It will be seen that the locking ring 26 serves not only to hold the ring 24 in position, but also clamps the guiding member 40 securely between the collar portion 42 and the ring surface 44. Furthermore, the pressure of the locking ring contracts the slotted lower portion of the collar 22, causing it to firmly grip the threaded outer surface of the cap 20.

The extreme lower end of the cap 20 is left smooth and unthreaded and is carefully finished to provide an additional guiding surface for the yarn on its path from the traveler T to the bobbin B.

By the provision of the guiding member 40, the effective operation of this type of cap spinning apparatus is much improved and all difficulty of unthreading the open type traveler is avoided. Furthermore, by providing the ring and traveler in combination with the guiding flange at the lower end of the cap 20, it is found possible to wind the yarn much more closely on the bobbin B and to thus increase the amount of yarn on each bobbin, correspondingly increasing the run of the bobbin.

Having thus described my invention and the advantages thereof, I do not wish to be limited to the details herein disclosed,

otherwise than as set forth in the claims, but what I claim is:—

1. In a spinning apparatus having a spindle, a bobbin mounted thereon and rotatable and axially movable relative thereto, and a cap mounted on the upper end of said spindle and depending about said bobbin, in combination, a spinning ring mounted on said cap and adjacent the lower end thereof, and a separate and additional annular yarn guiding member mounted on said cap and positioned below and adjacent said ring, the yarn guiding portion of said member having a diameter as large as the diameter of the largest part of said ring and engaging the yarn at a point substantially further from the axis of the cap than the lower edge of said cap.
2. The combination in a spinning apparatus as set forth in claim 1, in which the outer portion of the guiding member is outwardly and downwardly inclined.
3. The combination in a spinning apparatus as set forth in claim 1, in which a collar is provided on the cap on which the ring is mounted, and in which the guiding member is clamped between the collar and the ring.
4. The combination in a spinning apparatus as set forth in claim 1, in which the guiding member has an outwardly and downwardly inclined portion underlying the path of a traveler mounted on said ring.
5. The combination in a spinning apparatus as set forth in claim 1, in which a collar is provided at the lower end of the cap, said collar having a conical lower portion, and in which the guiding member is clamped against said conical collar portion and extends outwardly and downwardly to underlie the path of the traveler mounted on said ring.

In testimony whereof I have hereunto affixed my signature.

ELLIS HARTLEY.
